United States Patent Office.

J. D. WINSLOW, OF WILMINGTON, DELAWARE.

Letters Patent No. 65,146, dated May 28, 1867.

IMPROVED SASH-TIGHTENER.

The Schedule referred to in these Letters Patent and making part of the same.

Be it known that I, JACOB D. WINSLOW, of the city of Wilmington, in the State of Delaware, have invented a new and useful Sash-Tightener; and I do hereby declare that the following is a full, clear, and exact description of the construction and operation of the same, reference being had to the annexed drawings, making a part of this specification, in which—

Figure 1 is a front view of a window with the sash-tightener attached.

Figure 2, a transverse section of the same.

I construct my sash-fastener of iron, or any other suitable material, in the form of a wedge, which works or impinges against a pin or stop, as shown at *a* in the drawings. This sash-tightener may be reversed from the position shown by setting the pin or stop on the sash and the wedge-shaped tightener upon the beading. I am careful to construct the angle of the wedge so as not to impinge too heavily upon the stop, and so that the window-sash may be raised without difficulty. The tightener being in place when the sash is pushed up or down, as the case may require to close the sashes, the sash is driven close to the parting strip, thereby keeping out the air, and preventing the window from being rattled by the wind or storm.

What I claim as my invention, and desire to secure by Letters Patent, is—

The attaching to window-sashes the wedge-shaped piece *a*, together with the pin or stop *b*, as shown in the drawings, and herein described as a sash-tightener, to exclude wind and storms, and prevent the sash from rattling.
